(57) **CLAIM**

The ornamental design for a pocket knife, as shown and described.

DESCRIPTION

FIG. 1 is a top, front, right side perspective view of a pocket knife, showing my new design;
FIG. 2 is a bottom, rear, left side perspective view thereof;
FIG. 3 is a front, right side perspective view thereof;
FIG. 4 is a front elevational view thereof;
FIG. 5 is a rear elevational view thereof;
FIG. 6 is a left side elevational view thereof;
FIG. 7 is a right side elevational view thereof;
FIG. 8 is a top plan view thereof;
FIG. 9 is a bottom plan view thereof;
FIG. 10 is a front and right perspective view showing the pocket knife in folded state;
FIG. 11 is an enlarged view of the portion 11 in FIG. 1;
FIG. 12 is an enlarged view of the portion 12 in FIG. 2;
FIG. 13 is an enlarged view of the portion 13 in FIG. 2; and,
FIG. 14 is an enlarged view of the portion 14 in FIG. 3.
The dotted broken lines illustrate portions of the pocket knife and form no part of the claimed design. The unevenly dashed broken lines define the boundaries of enlarged views and form no part of the claimed design.
